(57) **CLAIM**

The ornamental design for a seat stand, as shown and described.

DESCRIPTION

FIG. 1 is a right side view of a seat stand;

FIG. 2 is a left side view of a seat stand;

FIG. 3 is a front view of a seat stand;

FIG. 4 is a rear view of a seat stand;

FIG. 5 is a top view of a seat stand;

FIG. 6 is a bottom view of a seat stand;

FIG. 7 is a top, right, rear perspective view of a seat stand;

FIG. 8 is a top, left, rear perspective view of a seat stand;

FIG. 9 is a top, right, front perspective view of a seat stand;

FIG. 10 is a top, left, front perspective view of a seat stand;

FIG. 11 is a bottom, right, rear perspective view of a seat stand; and,

FIG. 12 is a bottom, right, front perspective view of a seat stand.

The broken lines in the drawings illustrate portions of the seat stand that form no part of the claimed design.

1 Claim, 12 Drawing Sheets
